United States Patent Office

Des. 196,348
Patented Sept. 17, 1963

196,348

REFRIGERATOR DISPLAY CABINET

Abraham H. Bank, Doornfontein, Johannesburg,
Republic of South Africa

Filed Mar. 19, 1962, Ser. No. 69,338

Term of patent 14 years

(Cl. D80—11)

FIG. 1.

FIG. 2.

FIG. 3.

*FIG. 4.**FIG. 5.*FIGURE 1 is a front elevational view of a refrigerated display cabinet embodying my new design;

FIGURE 2 is an elevated view taken from one side thereof;

FIGURE 3 is a front perspective view thereof taken from the side opposite that shown in FIGURE 2;

FIGURE 4 is an elevational view taken from the rear thereof; and

FIGURE 5 is a plan view thereof.

The dominant features of my design reside in the portions shown in full lines.

I claim:

The ornamental design for a refrigerated display cabinet, as shown and described.
